UNITED STATES PATENT OFFICE.

FRANK J. CANTRELL, OF SAN FRANCISCO, CALIFORNIA.

CALCULATING-MACHINE.

1,251,180.

Specification of Letters Patent. Patented Dec. 25, 1917.

Application filed October 10, 1916. Serial No. 124,777.

To all whom it may concern:

Be it known that I, FRANK J. CANTRELL, a citizen of the United States, residing at the city and county of San Francisco and State of California, have invented new and useful Improvements in Calculating-Machines, of which the following is a specification.

This invention relates to a calculating machine.

In pipe fitting for steam, hot water connections, or plumbing in general, it is common practice to employ 45° elbows, $22\frac{1}{2}^\circ$ elbows, in fact a great variety of fittings are used extensively on different jobs. It therefore often becomes necessary to measure pipe lengths of triangular connections. Sometimes it is necessary to determine the hypotenuse, and in several instances either the short or the long leg of the triangle.

It is not very often that mechanics have mastered mathematics sufficiently to be able to figure the square root in order to find the hypotenuse of a triangle, similarly it is equally difficult to determine either side of a triangle.

The object of the present invention is to provide a simple, substantial calculating machine particularly adapted for determining any side of a triangle where one side and the angle of the hypotenuse is given.

Further objects will hereinafter appear.

The invention consists of the parts and the construction and combination of parts as hereinafter more fully described and claimed, having reference to the accompanying drawing, in which:—

Figure 1 is a cross section of the calculating machine.

Fig. 2 is a diagrammatic view showing the relation of two pipes desired to be connected.

Fig. 3 is a side elevation of the calculating machine.

Fig. 4 is a view of the table showing the long leg dimensions.

Fig. 5 is a similar view of the table showing the short leg dimensions.

Fig. 6 is a similar view showing the hypotenuse dimensions.

Referring to the drawings in detail, A indicates a triangular shaped casing consisting of three connected side members 2, 3 and 4, in each of which is formed an elongated window or reading slot 5. Forming a closure for this casing is a pair of end

sections 6 and extending through said end sections and the triangular casing as a whole, is a shaft 7 on the outer ends of which are secured turning knobs 8. Journaled between the end sections 6 are three pairs of shafts, 9, 10 and 11, each pair being positioned adjacent a reading slot 5, and each shaft is provided with a roller 12 which carries a chart such as shown in Figs. 4, 5 and 6. The rollers 9 carry the chart shown in Fig. 4 which contains the long leg dimensions of a triangle, the rollers 11, the chart shown in Fig. 5 which contains the short leg dimensions, rollers 10, and the chart shown in Fig. 6 which contains the hypotenuse dimensions.

Mounted on one end of the shaft 7 interior of the casing is a spur gear 13, and mounted on each roller shaft is a pinion 14 which intermeshes with the gear 13. Turning movement transmitted to shaft 7 through either knob 8, causes the gear 13 to turn in one direction or the other, and simultaneously transmits movement to all the intermeshing pinions 14 to turn these in unison with same. The chart carrying rollers 9, 10 and 11 will therefore turn in unison and move the individual charts across the reading slots 5, a strip 16 being placed below each reading slot to support the individual charts intermediate of the winding rollers. The side section 3 of the main casing is graduated as shown in Fig. 3 from $11\frac{1}{4}^\circ$ to 75° and is furthermore marked Long leg. The side sections 2 and 4 are similarly graduated each being marked according to the chart which is used, for instance the side section 2 carries the legend Short leg, while the side section 4 carries the legend Hypotenuse.

Each of the charts shown in Figs. 4, 5 and 6, are also graduated from $11\frac{1}{4}^\circ$ to 75° and each chart may be provided with dimensions commencing with one inch, and continuing up to as many feet as desired.

One of the essential features of the present invention is the moving of a plurality of charts in unison, and positively maintaining a fixed relation between the said charts at all times. If the charts are all wound about one roller, the relation between the same should be such that the first line of each chart stands in register with the coöperating reading slot. If the charts are turned until line 6 of one chart is in register with the reading slide, then line 6 of the other charts must also be in register with their coöperat-

- ing reading slots. The provision of the single driving gear 13 together with the intermeshing pinions 14, forms the necessary mechanism whereby a uniform movement and positive relation between the several charts is secured. This positive and direct drive, while limiting the extent of movement of the charts by reason of the differences in the radii of the coils as the charts are wound from one roll to the other, affords an accurate and durable operating mechanism for the three charts to actuate each sufficiently far to accomplish the desired computations.
- 15 The use of the instrument can better be described by referring to the piping diagram shown in Fig. 2. If it is desired to connect the pipe indicated at 20 with the pipe 21, it becomes necessary to measure 20 the length of the hypotenuse of the triangle indicated by dotted lines. This is easily accomplished in the present instance by either measuring the long leg or the short leg of the triangle.
- 25 If the long leg measures 2 ft. 8 inches (2' 8") the length of the hypotenuse can be determined by turning the charts until 2' 8" on the long leg chart is in register with the reading slot 5.
- 30 If the angle happens to be 45°, it will only be necessary to look through the reading slot on the hypotenuse side under 45°. The length of the hypotenuse will here be found to be 2' 10 $\frac{5}{8}$ ". This operation is practically 35 speaking instantaneous, as the only operation required is the turning of the central shaft by means of the knobs 8. If the hypotenuse of 2' 10 $\frac{5}{8}$ " is known, and it is desired to determine the short leg of the triangle, it is only necessary to turn the charts until 2' 10 $\frac{5}{8}$ " comes into register with the reading slot on the hypotenuse side. The corresponding short leg of the same angle will then be in register with the reading slot 40 formed on the short leg side of the casing. This reading shows 1' 14".
- 45 A calculating machine or instrument constructed as here shown is so simple and positive in action and so easily operated that 50 mistakes can hardly be made. It further-

more saves a great deal of time and worry on the part of the mechanic doing the pipe fitting, as only one measurement and the angle of the hypotenuse is required for any dimension wanted. The mechanic for this 55 reason merely takes the easiest measurement and determines the diagonal. He then turns the chart in the instrument until this dimension is secured, and as the other two corresponding dimensions will be found in the 60 opposite reading slots, it is obvious that mistakes such are commonly made when several dimensions are required and measured in the usual manner, are entirely obviated.

The materials and finish of the several 65 parts of the instrument may otherwise be such as the experience and judgment of the manufacturer may dictate.

I wish it understood that various changes in form, proportions and minor details of 70 construction may be resorted to within the scope of the appended claim, and that I do not wish to limit myself to the specific design or construction here shown.

Having thus described my invention, what 75 I claim and desire to secure by Letters Patent is:—

A calculator tool for use by plumbers and the like in determining triangles, composed of a casing having a triangular cross section 80 so that its sides conform to the sides and base of a triangle, each side having a sight opening with the respective legends "Long leg," "Short leg" and "Hypotenuse" associated therewith, a curtain for each sight 85 opening, the curtains bearing corresponding legends and having correlated dimension markings of varying sized triangles whereby when one dimension of a triangle is presented at its sight opening the remaining 90 side dimensions of the triangle will be presented at the other two sight openings, and means to operate the curtains in unison.

In testimony whereof I have hereunto set my hand in the presence of two subscribing 95 witnesses.

FRANK J. CANTRELL.
